[57] CLAIM

The ornamental design for a cover for a transport refrigeration unit, as shown and described.

DESCRIPTION

FIG. 1 is a perspective view of a cover for a transport refrigeration unit showing our new design;

FIG. 2 is a front elevational view thereof;

FIG. 3 is a top plan view thereof;

FIG. 4 is a left-hand elevational view thereof; and
FIG. 5 is a right-hand elevational view thereof.

The bottom of the cover is plain and unornamented.
The fragmentary broken line representation of the front
of a truck in FIG. 1 is for purposes of illustration only,
and forms no part of the claimed design.
